Specification for Design.

Patented Oct. 7, 1919.

Application filed May 29, 1919. Serial No. 300,741. Term of patent 14 years.

To all whom it may concern:

Be it known that I, HERMAN FRANKLIN, a citizen of the United States, residing at New York, in the county and State of New York, have invented a new, original, and ornamental Design for Statues, of which the following is a specification, reference being had to the accompanying drawings, forming part thereof.

The Figure 1 is a front elevation of the statue, showing my new design and Fig. 2 is a side elevation thereof.

I claim:

An ornamental design for a statue as shown.

HERMAN FRANKLIN.
